Fig. 6.

FIG. 1 is a top plan view of a drawer pull showing my new design;

FIG. 2 is a bottom plan view thereof;

FIG. 3 is a front elevational view;

FIG. 4 is a rear elevational view;

FIG. 5 is an end elevational view looking at the left end of FIG. 1; and

FIG. 6 is an end view as seen from the right end of FIG. 1.

The characteristic features of my design reside in the specific configuration of the end portions in association with the conventional gripping means, all as shown.

I claim:

The ornamental design for a drawer pull, as shown and described.
